LADDER BRACKET

Walter L. Brensike, Appleton, and Harold R. Brensike, New London, Wis.

Application December 1, 1950, Serial No. 198,668

5 Claims. (Cl. 248—238)

1

This invention relates to a novel construction of bracket to be used in pairs with a platform and a pair of ladders to provide a scaffold and has for its primary object to provide platform supporting brackets for supporting a platform at a plurality of elevations between adjacent rungs or steps of a pair of ladders.

More particularly, it is a primary object of the present invention to provide a bracket which functions effectively with a pair of ladders or other trestles for supporting a platform at a plurality of elevations which vary only slightly so that workmen standing upon the platform will be at a proper elevation for ceiling work thereby eliminating the inconvenience and loss of time frequently resulting when a scaffold platform is disposed either too high or too low to conveniently support workmen for ceiling work and which is necessarily true when the steps or rungs of ladders are employed for supporting the platform, due to the fact that ladder rungs or steps are usually spaced at least twelve inches apart.

Still a further object of the invention is to provide a ladder bracket of extremely simple construction which may be economically manufactured and sold and which will be extremely efficient and durable for accomplishing its intended result.

Another object of the invention is to provide a ladder bracket which may be quickly and easily applied to or removed from a ladder without the use of fastenings and which will be effectively supported thereon primarily by a ladder rung or step and secondarily by the side stiles of the ladder.

Various other objects and advantages of the invention will hereinafter become more fully apparent from the following description of the drawing, illustrating a presently preferred embodiment thereof, and wherein:

Figure 1 is a front elevational view of a preferred form of the bracket shown applied to a stepladder and illustrating two levels at which an end of a platform may be supported thereon;

Figure 2 is a fragmentary view similar to Figure 1 but showing the bracket adjusted for supporting an end of a platform at a third, higher level;

Figure 3 is a vertical sectional view taken substantially along a plane as indicated by the line 3—3 of Figure 1;

Figure 4 is a similar view taken substantially along a plane as indicated by the line 4—4 of Figure 2;

Figure 5 is a perspective view of the ladder bracket shown detached from the ladder, and

2

Figure 6 is a fragmentary perspective view of another embodiment of the ladder bracket.

Referring more specifically to the drawing and first with reference to Figures 1 to 5, the ladder bracket in its entirety is designated generally 7 and includes an elongated loop-shaped member, designated generally 8 which may be formed from a rod the ends of which may be suitably secured together or which may be formed from an endless member. The loop-shaped member 8 includes corresponding parallel portions 9 and 10.

A pair of corresponding steps or rung engaging hooks, each designated generally 11 is connected to the bracket portion 9, said hooks 11 each including a relatively long shank 12 having a sleeve 13 at one end through which the bracket portion 9 extends and in which it is slidably and turnably mounted. If the loop 8 is of integral construction rather than being formed from a rod the end portions of which are secured together or left unsecured and in substantially abutting relationship, the sleeves 13 will be of split construction but otherwise may be of uninterrupted construction and may be applied to the portion 9 before the ends of the rod forming the loop 8 are joined together. Each shank 12 at its opposite, upper end terminates in an elongated hook portion 14 which is adapted to engage over a step or rung 15 of a ladder or other suitable trestle 16 and each hook portion 14 has a downturned terminal or bill portion 17 which engages the inner edge of a rung or step 15 while the upper portion of the hook shank 12 engages the outer edge of said rung or step.

A pair of clips, each designated generally 18 is slidably and swingably mounted on the bottom loop portion 10, each clip including a sleeve 19 which slidably and turnably engages the loop portion 10, a shank 20 which projects radially from the sleeve 19 and an offset hook portion 21 which is offset relatively to the shank 20 and extends laterally from the free end thereof. In the embodiment of Figures 1 to 5, the hook portions 21 extend inwardly with respect to one another, as best seen in Figure 5.

As clearly illustrated in Figures 1 and 2, the loop portion 8 is of a length greater than the distance between the side stiles 22 of the ladder 16 and the hook shanks 12 are each of a length substantially greater than the spacing between the remote edges of the loop portions 9 and 10. Only a single ladder or trestle 16 and a single bracket 7 has been illustrated in Figures 1 to 4 but it will be understood that a pair of the brackets 7 are utilized with a pair of ladders or trestles 16 and that each bracket 7 is adapted

to adjustably support an end of a platform 23 which combines with the pair of brackets and the pair of ladders to form a scaffold. Assuming that the platform 23 if supported on the step or rung 15 to which the hooks 11 are connected would be disposed at too high a level for ceiling work or if supported on the rung or step 15 directly below the bracket 7 would be disposed too low for ceiling work, the bracket 7 is utilized for supporting an end of the platform 23 at three different elevations between said ladder steps and it will likewise be apparent that the opposite end, not shown, of the platform 23 will be similarly supported by a second bracket 7 mounted on a second ladder 16.

The bracket 7 is applied to the ladder 16 by engaging the hook portion 14 with a step or rung 15 of said ladder, as clearly illustrated in Figures 3 and 4, and as previously described. The end portions of the loop 8 will then bear against the outer edges of the stiles 22 to prevent the bracket 7 from swinging downwardly and inwardly relatively to the ladder 16 and to maintain it in its inclined position of Figures 3 or 4. With the loop 8 in a depending position relatively to the hooks 11, as illustrated in Figures 1 and 3, an end of the platform 23 may be supported by the loop portion 10 as illustrated in full lines in Figures 1 and 3 and which constitutes the lowermost level at which the platform can be supported by the bracket. If it is desired to support the platform at a slightly higher level this can be accomplished without any change in position of the bracket 7 by merely supporting an end of the platform on the loop portion 9 between the hooks 11, as illustrated in dotted lines in Figures 1 and 3. If it is desired to support the platform 23 at a higher level than its dotted line position of Figures 1 and 3, the loop portion 9 is rotated in the sleeves 13 counterclockwise as seen in Figure 3 to position the loop portion 10 above the loop portion 9 and against the outer sides of the hook shanks 12, as illustrated in Figures 2 and 4, and an end of the platform 23 is then supported on the loop portion 10 at a higher level than the dotted line position of the platform 23 of Figures 1 and 3. In order to insure that the loop 8 will not swing downwardly from its position of Figure 4 back to its position of Figure 3 accidentally and while the platform 23 is supported thereon, the clips 18 are engaged behind the hook shanks 12, as seen in Figures 2 and 4, to retain the loop 8 in its position of these figures, this being accomplished by moving the clips 18 outwardly to adjacent the ends of the loop portion 10 before said portion is swung upwardly and thereafter displacing the clips 18 inwardly until their hook portions 21 engage behind the hook shanks 12. It will thus be readily apparent that an end of the platform 23 may be supported at three different elevations between two adjacently disposed rungs or steps 15 so that, for example, if the steps or rungs 15 are spaced twelve inches apart an end of the platform 23 could be supported approximately three inches, six inches or nine inches above the lower of the two rungs or steps or beneath the upper of said two rungs or steps.

Figure 6 illustrates a slightly different embodiment of the ladder bracket, designated generally 7a wherein in lieu of the loop 8 a pair of rods 9a and 10a are provided. Said rods 9a and 10a are connected adjacent their ends by a pair of connectors 24 each including a bar 25 having an integral transversely disposed sleeve 26 at each end thereof. The sleeves 26 of each connector

24 are slidably and turnably connected, one to each of the rods 9a and 10a. The bracket 7a also includes a pair of hooks 11a corresponding to the hooks 11 and which function in exactly the same manner and for the same purpose. The sleeves 13a of the hooks 11a slidably and turnably engage the rods 9a between the sleeves 26 which are connected to said rod. A pair of clips 18a is slidably mounted on the rod 10a between the connectors 24 and differ from the clips 18 only in the fact that their hook portions 21a extend outwardly instead of inwardly with respect to one another as said clips 18a are displaced away from one another into engagement with the hook shanks 12a and toward one another to be disengaged therefrom.

As the operation and manner of use of the bracket 7a is identical with the bracket 7, a further description thereof is considered unnecessary.

Various other modifications and changes are likewise contemplated and may obviously be resorted to, without departing from the spirit or scope of the invention as hereinafter defined by the appended claims.

We claim as our invention:

1. A ladder bracket comprising a pair of hooks each adapted to detachably engage over a ladder rung or step and each provided with an elongated depending shank adapted to extend downwardly from an edge of the step or rung, a rigid elongated member having spaced portions connected to lower portions of the hook shanks and disposed transversely of said hook shanks, a second elongated member, and means connecting said elongated members outwardly of said hook shanks in spaced substantially parallel relationship and normally supporting said second elongated member beneath the first mentioned elongated member, said elongated members being adapted to be disposed beneath the step or rung engaged by the hooks and above the step or rung disposed directly therebeneath for selectively supporting an end of a platform on either of said elongated members at different levels relatively to the step engaged by the hooks, said first mentioned elongated member being turnably and slidably connected to the hook shanks whereby the second elongated member is swingable upwardly to a position above the first mentioned elongated member and against the hook shanks for supporting an end of the platform above the level of the first mentioned elongated member.

2. A ladder bracket comprising a pair of hooks each adapted to detachably engage over a ladder rung or step and each provided with an elongated depending shank adapted to extend downwardly from an edge of the step or rung, a rigid elongated member having spaced portions connected to lower portions of the hook shanks and disposed transversely of said hook shanks, a second elongated member, and means connecting said elongated members outwardly of said hook shanks in spaced substantially parallel relationship and normally supporting said second elongated member beneath the first mentioned elongated member, said elongated members being adapted to be disposed beneath the step or rung engaged by the hooks and above the step or rung disposed directly therebeneath for selectively supporting an end of a platform on either of said elongated members at different levels relatively to the step engaged by the hooks, said elongated members constituting corresponding parallel portions of

an elongated loop having integral end portions joining complementary ends of said elongated members.

3. A ladder bracket comprising a pair of hooks each adapted to detachably engage over a ladder rung or step and each provided with an elongated depending shank adapted to extend downwardly from an edge of the step or rung, a rigid elongated member having spaced portions connected to lower portions of the hook shanks and disposed transversely of said hook shanks, a second elongated member, and means connecting said elongated members outwardly of said hook shanks in spaced substantially parallel relationship and normally supporting said second elongated member beneath the first mentioned elongated member, said elongated members being adapted to be disposed beneath the step or rung engaged by the hooks and above the step or rung disposed directly therebeneath for selectively supporting an end of a platform on either of said elongated members at different levels relatively to the step engaged by the hooks, said elongated members constituting substantially parallel portions of a rod formed in the shape of an elongated loop.

4. A ladder bracket comprising a pair of hooks each adapted to detachably engage over a ladder rung or step and each provided with an elongated depending shank adapted to extend downwardly from an edge of the step or rung, a rigid elongated member having spaced portions connected to lower portions of the hook shanks and disposed transversely of said hook shanks, a second elongated member, and means connecting said elongated members outwardly of said hook shanks in spaced substantially parallel relationship and normally supporting said second elongated member beneath the first mentioned elongated member, said elongated members being adapted to be disposed beneath the step or rung engaged by the hooks and above the step or rung disposed directly therebeneath for selectively supporting an end of a platform on either of said elongated members at different levels relatively to the step engaged by the hooks, said means for connecting the rods comprising a pair of connectors each including a bar having transverse sleeve portions

at the ends thereof engaging said elongated members.

5. A ladder bracket comprising a pair of hooks each adapted to detachably engage over a ladder rung or step and each provided with an elongated depending shank adapted to extend downwardly from an edge of the step or rung, a rigid elongated member having spaced portions connected to lower portions of the hook shanks and disposed transversely of said hook shanks, a second elongated member, and means connecting said elongated members outwardly of said hook shanks in spaced substantially parallel relationship and normally supporting said second elongated member beneath the first mentioned elongated member, said elongated members being adapted to be disposed beneath the step or rung engaged by the hooks and above the step or rung disposed directly therebeneath for selectively supporting an end of a platform on either of said elongated members at different levels relatively to the step engaged by the hooks, said first mentioned elongated member being turnably and slidably connected to the lower, free ends of the hook shanks whereby the second elongated member is swingable upwardly to a position above the first mentioned elongated member and against the hook shanks for supporting an end of the platform above the level of the first mentioned elongated member, and clips slidably and turnably connected to the second elongated member having hook portions spaced therefrom and movable into engagement with the hook shanks for retaining said second elongated member in a position against the hook shanks and above the first mentioned elongated member.
